CLOCK WINDING MECHANISM

Sylvanus W. Bramley, White Plains, N. Y.

Application June 12, 1944, Serial No. 539,945

8 Claims. (Cl. 185—40)

1

This invention relates to automatic clock winding mechanism, more particularly of the type in which an electromagnetic circuit is employed. In this type of apparatus energy is stored in a spring by the movement of an armature of an electromagnet. The energy of the spring is then employed to operate a train of clock mechanism. When the energy of the spring is partly dissipated, electrical contact is made which again energizes the magnet and restores energy to the spring.

Numerous mechanisms of this type have been proposed, notably for use on vehicles, such as automobiles. Practical difficulties have however been met in providing a mechanism which will be sufficiently reliable in its operation to provide accuracy of time keeping. It is an object of the present invention to provide improved mechanism to solve the problems which have arisen, to provide improved electrical and mechanical make and break mechanism, and in general, to provide improved electrical and mechanical means simple in construction and adapted for long-continued operation to provide reliable, accurate time recording.

The invention will be defined in the claims and described in the following description taken in conjunction with the appended drawings in which

Fig. 1 is a plan view taken on the line 1—1 of Fig. 2,

Fig. 2 is a side view showing the clock with the casing removed to show the clock mechanism.

Fig. 3 is a plan view generally similar to Fig. 1 showing the relative positions of armature and electromagnet when the main spring is fully tensioned, that is, when the clock is fully wound up, Fig. 1 showing the relative positions of armature and electromagnet in the "run down" position,

Fig. 4 is a view similar generally to Figs. 1 and 3 showing the relative positions of armature and electromagnet intermediate the positions shown in Figs. 1 and 3,

Fig. 5 is a reverse view of the mechanism shown in Fig. 1,

Fig. 6 is a view partly in section on the line 6—6 of Fig. 5,

Fig. 7 is a view similar to that shown in Figs. 1, 3 and 4 with, however, all parts removed except the electromagnet and its electrical connections,

Fig. 8 is a diagrammatic view illustrating the electrical circuit employed,

Fig. 9 is an enlarged detail view showing the special structure of the make and break contact means,

Fig. 10 is a section on line 10—10 of Fig. 11,

2

Fig. 11 is an elevational side view of a modified form of the invention,

Fig. 12 is a view partly in section on the line 12—12 of Fig. 11,

Fig. 13 is a sectional view on line 13—13 of Fig. 12,

Fig. 14 is a sectional view on line 14—14 of Fig. 13,

Fig. 15 is an enlarged view of a part of the switch mechanism,

Fig. 16 is a diagrammatic view of the electrical connections and switch mechanism,

Fig. 17 is an enlarged fragmentary view of a part of the switch mechanism, and

Fig. 18 shows another switch mechanism and associated parts.

In the several views like parts are shown by the same numerals.

Referring to Figs. 1 to 9, an electromagnet 1, including core 2, pole pieces 3, 4, and coil 5, is mounted on the plate 6, the pole pieces 3, 4 being secured to the plate 6 by screws 7 and the coil 5 being in spaced relation to said plate. Insulation pieces not shown in the drawings insulate the ends of the coil from the pole pieces. The binding post 8 passes through an aperture in the plate and is insulated therefrom by insulation 10, the post 8 being securely held in place by metallic gaskets 11, to one of which one end of the coil is electrically connected as by soldering 12. The other end of the coil is secured in metallic and electrical connection with the plate by means of a screw or rivet 13. Adjacent the pole piece 3, there is mounted on the plate 6 and insulated therefrom by the insulation 15, a small plate 14 carrying an upstanding pin 20 extending transversely to the plate 14. The pin 20 is made of pure silver and the plate 14 of which the pin 20 is an extension may also be made of silver for the sake of convenience although the said plate 14 may be made of other metallic material, e. g. brass, to which the pure silver pin 20 may be joined by brazing. Secured to the plate 14 is the binding post 21 which passes through apertures in both plates and is insulated from the plate by insulation pieces 15 and 22. The post 21 is held in firm engagement with the said insulation and plates 6 and 14 by means of a gasket or washer.

The train of clock mechanism indicated generally as is conventional. This mechanism is mounted on segmental parts 24, 25, and 26 which in turn are mounted on posts 27 secured to the plate 6. The clock dial 28 is secured to the segmental part 25 by brackets 29. The said conventional mechanism includes a ratchet wheel

30 secured to a hub 31 carried by an arbor 18 rotatably mounted at one end on a fixed mandrel 32. The arbor near the other end is journaled in segment 25, passes through an aperture in the dial and carries hands 33 of the clock which are rotated by the mechanism actuated by rotation of the said ratchet wheel 30 and arbor 18. The fixed mandrel 32 is secured in and mounted on a yoke which includes the flat strip 40 supported on and secured to posts 41, 42 which in turn are mounted on and secured to the segment 26. Intermediate between the ratchet wheel 30 and the strip 40, the armature 43 is rotatably mounted on said mandrel 32. The armature 43 comprises a flat strip of soft iron having end portions 44, 45 extending transversely thereof and arranged to sweep over, i. e. to be brought in closely spaced relation to the corresponding ends of the pole pieces 3, 4. For this purpose the said ends 44, 45 of the armature are arcuately shaped to correspond to the complementary shape of the pole pieces 3, 4. The armature 43 is therefore adapted to rotate about an axis perpendicular to the plate 6 and perpendicular to the longitudinal axis of the electromagnet. The rotational axis of the armature passing through the mid point of the electromagnet and being transverse to the longitudinal axis of said armature. The latter axis lies in a plane parallel to the plane containing the longitudinal axis of the electromagnet. To the armature and intermediate the axis of rotation and one end of said armature, there is secured one end of the spring 50 by means of a pin or rivet 51, the other end of the spring being secured to an extension 52 of the yoke piece or strip by means of the pin 53. Near the ends of the armature 43 and pivoted thereon by the pins 54 are the pawls 55, 56 arranged to engage the ratchet wheel 30, these pawls being biased by spring members 57. One end of each spring is inserted in a hole and then bent around a post 59 and into engagement with its pawl.

On the side of the armature opposite the side to which the spring is attached, there is provided an extension or lug 60 carrying a pivot pin 61 extending transversely to said extension. On this pivot pin 61 an arm 62 is pivotally mounted and is biased to occupy the positions shown in Figs. 3 and 4 by means of a coil spring 63, aided by spring 67, one end of which is secured to the lug 60, the other end bearing against a portion 64 of the arm bent at right angles, said bent portion being adapted to engage the armature 43 at one position of movement of said pivoted arm. The said pivoted arm carries a soft iron shoe portion 65 which is arranged to cooperate with a strip 70 constituting an extension of the pole piece 3 and secured thereto by means of screws 71. The pivoted arm may be as shown, a flat strip from which the shoe portion 65 extends transversely. The arm as shown in the drawings terminates in a portion 72 which extends transversely both to the plane of the arm and also to the plane of the flat shoe 65 and from that terminal portion of the arm, there extends a pin made of pure silver. It is this movable pin 73 which cooperates with the fixed pin 20, said pins constituting the electrical contact or make and break elements. As shown clearly in the various views, including particularly Fig. 9, the axes of the pins 20 and 73 are at right angles for purposes which will be more fully hereinafter described.

The electrical circuit connections are shown

clearly in Fig. 8. The clock containing the mechanism of the present invention is adapted to be operated from any suitable source of current, as for example, the battery 80. As shown in Fig. 8, the positive and negative lead wires 81 and 82 from the battery are insulated from the plate 6 (by connection to the binding posts which are in turn insulated by means of insulation members). Tracing the course of the current, it passes from the positive terminal of the battery through the lead wire 81, then through the coil 5 surrounding the core, and from there to the plate 6 through the wire 82 and the pin or rivet 13 secured to the plate 6 as clearly shown in Fig. 7 and as indicated in Fig. 8 by the point 83. The plate 6 is in electrical connection with the armature through structural elements, including the posts 27, one of which is shown clearly in Fig. 2, the segments 25, 26, the hub 31, and the mandrel 32 on which the armature is rotatably mounted. The arm 62 pivotally mounted on the armature 43 is also in electrical connection with the latter, this electrical connection being further facilitated by the coil spring 63. Therefore, the pivoted arm 62 and the pin extension 73 thereof are in electrical connection with the plate 6 and therefore the coil 2. In Fig. 8 this electrical connection between the plate and the pivoted arm is diagrammatically shown by the lead wire 84. No such lead wire is however necessary in the practical construction of the mechanism. Tracing the course of the current still further and assuming contact between the pins 20 and 73, the current then passes from the pin 73 to the pin 20 and then through the lead wire 82 back to the negative terminal of the battery. To protect the entire mechanism against excessive current the plate 6 may be grounded as shown.

In the operation of the device, and assuming that the armature has been rotated clockwise by tension on the spring 50 as far as the armature will go, e. g. against post 66, this rotation of the armature (note Fig. 1) moves the pivoted arm 62 into a position where the contact pins 73, 20 are brought into engagement. (Note Fig. 1). The electrical circuit is then closed and the electromagnet 1 energized. A pull is then exerted on the armature 43 tending to rotate it counter-clockwise and this pull exerts its effect as long as the said pins 73, 20 are in contact. As previously stated and as clearly shown, the axes of these two pins are at right angles. When the armature is in its ultimate position of movement in a clock-wise direction the end of the pin 73 extends a substantial distance beyond the axis of the pin 20. In the counter-clockwise movement of the armature the pin 73 is drawn transversely across the pin 20 by the rotation of the lug 60 on which the pivoted arm 62 is mounted, this lug 60 having an offset position in relation to the axis about which the armature 43 rotates. The electrical connection is not broken until there is a complete disengagement of the pin 73 from the pin 20, which requires an appreciable interval and provides for movement of the armature to its ultimate counter-clockwise position, during which movement the spring is fully tensioned. There is therefore an appreciable time of contact of the pins in moving electrical contact with each other. Stated otherwise, the electrical contact is preserved until the clock is fully wound up. A sudden make and break would not accomplish this purpose and would only partially tension the spring and thus develop correspondingly less energy for driving the clock operating mecha-

nism. By the means described, a maximum amount of energy in the spring is developed with a corresponding increase in the time required to exhaust that energy. Thus the period of time during which the clock "runs down" is lengthened and the total number of breaks in the electrical circuit in any given time interval are reduced. Furthermore, by making the pins of pure silver, the formation of insulating coatings or scale is prevented and there is always a substantially perfect contact of metallic silver to metallic silver, thus establishing certainty of operation.

The maintenance of the pins 73 and 20 (which constitute the control switch) in contact during the counter-clockwise movement of the armature 43 is facilitated by strip 70 which concentrates the magnetic flux and cooperates with the magnetic shoe member 65.

When the spring is fully tensioned, the contacts 20, 73 are separated, this separation being facilitated by the coil spring 63 which biases the pivoted arm 62 (note Figs. 3 and 4) to separate said contacts; tension on the spring 50 then causes clockwise rotation of the armature, this rotation being transmitted to the ratchet wheel 30 and thence to the hands of the clock by means of the pawls 55, 56. During tensioning of the spring and counter-clockwise rotation of the armature, tension to drive the ratchet wheel is maintained by a coil spring (not shown in the drawings) located within the drum 31.

Figs. 10 to 16 show a modified form of the invention. The electromagnet 1 is mounted on a base 90 of insulating material having apertures through which binding posts 8 and 21 pass secured to said base by nuts 91, 92 with which nuts 93, 94 cooperate to secure lead wires from the battery 80. One end of the coil 2 is soldered or brazed to binding post 8. The other end is connected to switch 95 shown diagrammatically and in perspective in Fig. 16. This switch comprises an insulating member 96 supported on a bracket 97 secured to binding post 21. The insulating member 96 insulates two small bars or strips 98, 99 (note Fig. 17) from each other except when they are placed in electrical communication by means to be described. The strips 98, 99 are made of pure silver. Strip 98 is brazed to the bracket 97 which may be brass or bronze. Strip 99 is connected to bar 99A which in turn is connected to bracket 99B secured to base 90 by screw 99C. To bracket 99B is secured one end of coil 5 and insulating member 96 is secured between brackets 97 and 99B and insulates these from each other. The other part of the switch comprises two cooperating bars 100, 101 of pure silver brazed to an elongated U-shaped member 102 which may be made of Phosphor bronze and which is an extension of the member 103 forming a part of arm 62. The latter is pivoted by means of pivot pin 61 on a bracket 104 secured to armature 43 by rivet 105. Arm 62 is biased by coil spring 63 mounted on pivot pin 61 one end of said spring being secured to bracket 104 and the other end to arm 62. Arm 62 has a lug 106 adapted to engage bracket 104 which acts as a stop and limits movement of said arm 62 in one direction. The member 103 is a strip which may be made of Phosphor bronze and is stiffened by upstanding edge portions 107. On its under side said strip 70 carries a soft iron magnetic shoe 65 cooperating with strip 70 constituting an extension of pole piece 3. To the shoe 65 there is attached a non-magnetic strip 108 which acts to provide spacing between strip 70 and the magnetic shoe piece 65.

Referring to Figs. 10, 11, and 13, the armature 43 is rotatably mounted on fixed mandrel 32 secured in strip 40 supported by posts 41, 42. On this mandrel is also rotatably mounted ratchet wheel 30 secured to arbor 18 which is suitably journaled as in segment 25. The rotation of the ratchet wheel and arbor actuates the clock mechanism and the indicating hands 33 mounted on the arbor at one end thereof. The armature 43 has a housing portion 109 within which coiled main spring 110 is located secured by pin 111 to said housing at one end and secured to the fixed mandrel 32 at the other end 112 thereof. An auxiliary housing 113 secured to the strip 40 further encloses said spring 110.

On the armature 43 pawls 55, 56 are pivoted on pins 54 and biased by coil springs 120.

The operation of the mechanism described in Figs. 10 to 17 inclusive will now be described. Assume that the mechanism is in the "run down" condition as shown by the position of the armature 43 in Fig. 10. This causes the arm 62 to be swung so that the U-shaped switch member 102 bridges the contacts 98, 99 thereby establishing a closed electrical circuit from the battery through the coil to around the electromagnet 1. The energized electromagnet then causes rotation of the armature 43 in a counter-clockwise direction. During this movement the electrical circuit is maintained in closed position or condition as long as the U-shaped switch member 102 bridges the contacts 98, 99. The time of circuit closing that is duration thereof is controlled by the length of the contacts or bars 98, 99 and the extent to which the legs of the U-shaped member 102 extend beyond said contacts 98, 99 (note Figs. 11 and 13) and the structure of the part is arranged in the manner taught herein so that the circuit shall remain closed until, by rotation of the armature, the main spring of the mechanism is fully wound up and acquires sufficient energy to operate the mechanism during a light substantial interval of time in order to reduce to a minimum the total number of makes and breaks occurring during the life of the mechanism. The magnitude of energy stored in the main spring 110 is dependent on the angle through which armature 43 rotates in a counter-clockwise direction and the magnitude of this angle is in turn dependent on the time during which the electrical circuit remains in a closed position. This maintenance is facilitated by the member 103 to which is attached the magnetic shoe 65 which cooperates with the extension 70 of the pole piece 3 to hold the U-shaped switch member 102 in circuit closing position until the armature 43 is fully rotated through its predetermined angle of rotation in order to fully wind the main spring 110. At the end of the movement of the armature in a counter-clockwise position it is necessary that the circuit be immediately broken and to facilitate this action coil spring 63 is provided to throw the arm 62 away from the contact 98, 99. The non-magnetic strip 108 provides sufficient air gap between magnetic shoe 65 and the extension 70 of pole piece 3 to prevent freezing of the part by residual magnetism remaining after the circuit is broken. When the coil spring or main spring 110 is fully stressed by counter-clockwise rotation of the armature 43, and the circuit is broken, the energy in said spring then causes operation of the clock mechanism by causing rotation of said armature in a clockwise direction this rotation being communicated to the ratchet wheel 30 by the pawls 55, 56.

During winding of the main spring 110, rotation of the ratchet wheel is maintained by a maintaining spring located within hub 31, this maintaining spring not being specifically shown.

Referring to Fig. 18, 121 indicates a tube which may be made of glass secured to the armature 43 and having terminals or electrodes sealed into one end thereof, these terminals being connected to lead wires. This tube is a part of an electrical circuit including the battery and the electromagnet shown in Figs. 8 and 16 for example. That is to say, the tube 121 with its electrodes constitutes a switch which is a part of that electrical circuit. The tube contains a globule of mercury which causes closing of the switch when the tube is tilted into the position shown. The armature 43 and the electromagnet 1 are so arranged that the switch 121 occupies the circuit closing position shown in Fig. 18 when the main spring 110 is run down. Thereupon the closing of the circuit energizes the electromagnet, rotates the armature 43 into the position shown in broken lines in Fig. 18 whereupon the globule of mercury runs to the other end of the tube and causes breaking of the circuit. The arrangement shown in Fig. 18 is not claimed herein. It is different from the switch mechanism described and claimed.

What is claimed is:

1. In apparatus of the character described, in combination an electromagnet having a longitudinal axis and a pair of poles, an elongated armature pivoted to rotate about an axis passing through the mid-point of the electromagnet and perpendicular to the axis thereof, said armature having a longitudinal axis perpendicular to its rotational axis, said longitudinal axis lying in a plane parallel to the plane containing the longitudinal axis of the electromagnet and said armature having end pieces arranged to sweep over the pole pieces of the electromagnet, a spring biasing said armature to rotate it in clockwise direction and to thereby operate the clock mechanism, said armature being arranged to rotate through an angle of predetermined magnitude alternately in a clockwise and counter-clockwise direction, the position of the armature at the end of its movement in a clockwise direction corresponding to a run down condition of the spring and the position of the armature at the end of its counter-clockwise movement corresponding to a fully re-stressed condition of the spring, a switch including a fixed elongated bar and a movable contact, and means to close said switch at the end of the clockwise movement of the armature, to maintain said switch in closed position during the counter-clockwise movement of the armature and until the spring is fully re-stressed, said means including an arm pivoted on said armature to rotate about an axis parallel and in spaced relation to the rotational axis of said armature and offset from the longitudinal axis of said armature said arm carrying said movable bar and being adapted for longitudinal movement in the direction of the longitudinal axis of said bar; said fixed contact being adjacent one pole of the magnet which pole is cooperatively arranged in relation to one end of the armature and the axis of rotation of said arm being intermediate the rotational axis of the armature and the other end thereof, the armature, movable arm and switch members being thereby arranged to effect closing of said switch at the end of the clockwise movement of the armature and to effect movement of the movable elongated bar in sliding

engagement with the fixed contact during counterclockwise movement of said armature and whereby the switch is maintained in a closed condition during contact of said elongated bar with the fixed contact and opened by disengagement of the movable bar and fixed contact at the end of said longitudinal movement.

2. In apparatus of the character described, in combination an electromagnet having a longitudinal axis and a pair of poles, an elongated armature pivoted to rotate about an axis passing through the mid-point of the electromagnet and perpendicular to the axis thereof, said armature having a longitudinal axis perpendicular to its rotational axis, said longitudinal axis lying in a plane parallel to the plane containing the longitudinal axis of the electromagnet and said armature having end pieces arranged to sweep over the pole pieces of the electromagnet, a spring biasing said armature to rotate it in clockwise direction and to thereby operate the clock mechanism, said armature being arranged to rotate through an angle of predetermined magnitude alternately in a clockwise and counter-clockwise direction, the position of the armature at the end of its movement in a clockwise direction corresponding to a run down condition of the spring and the position of the armature at the end of its counter-clockwise movement corresponding to a fully re-stressed condition of the spring, a switch including a pair of electric contact pins one of said pins being fixed and the other movable, the axes of said pins being transverse to each other, and means to close said switch at the end of the clockwise movement of the armature, to maintain said switch in closed position during the counter-clockwise movement of the armature and until the spring is fully re-stressed and then to open said switch, said means including a pivot on said armature and an arm pivoted on said pivot armature to rotate about an axis parallel and in spaced relation to the axis of rotation of said armature, said arm carrying said movable contact pin, said armature and pivoted arm thereon being arranged to cause the end of the movable pin on said arm to extend beyond and in contact with the fixed pin when the armature is at the end of its clockwise movement and to draw said movable pin across and in contact with the fixed pin during counter-clockwise motion of the armature and to open said switch by said drawing movement, the said pivot moving away from said fixed contact during said counter-clockwise motion.

3. In apparatus of the character described, in combination an electromagnet having a longitudinal axis and a pair of poles, an elongated armature pivoted to rotate about an axis passing through the mid-point of the electromagnet and perpendicular to the axis thereof, said armature having a longitudinal axis perpendicular to its rotational axis, said longitudinal axis lying in a plane parallel to the plane containing the longitudinal axis of the electromagnet and said armature having end pieces arranged to sweep over the pole pieces of the electromagnet, a spring biasing said armature to rotate it in clockwise direction and to thereby operate the clock mechanism, said armature being arranged to rotate through an angle of predetermined magnitude alternately in a clockwise and counter-clockwise direction, the position of the armature at the end of its movement in a clockwise direction corresponding to a run down condition of the spring and the position of the armature at the end of its counter-

clockwise movement corresponding to a fully re-stressed condition of the spring, a switch including a fixed contact and a movable contact, and means to close said switch at the end of the clockwise movement of the armature, to maintain said switch in closed position during the counter-clockwise movement of the armature and until the spring is fully re-stressed, said means including an arm pivoted on said armature to rotate about an axis parallel and in spaced relation to the rotational axis of said armature and offset from the longitudinal axis of said armature said arm carrying said movable contact; said fixed contact being adjacent one pole of the magnet which pole is cooperatively arranged in relation to one end of the armature and the axis of rotation of said arm being intermediate the rotational axis of the armature and the other end thereof, the armature, movable arm and switch members being thereby arranged to effect closing of said switch at the end of the clockwise movement of the armature and to effect movement of the movable contact in sliding engagement with the fixed contact during counter-clockwise movement of said armature; and cooperating magnetic elements on said pivoted arm and electromagnet respectively, to maintain said switch in closed condition by maintaining said sliding engagement during counter-clockwise movement of said armature.

4. In apparatus of the character described, in combination an electromagnet having a longitudinal axis and a pair of poles, an elongated armature pivoted to rotate about an axis passing through the mid-point of the electromagnet and perpendicular to the axis thereof, said armature having a longitudinal axis perpendicular to its rotational axis, said longitudinal axis lying in a plane parallel to the plane containing the longitudinal axis of the electromagnet and said armature having end pieces arranged to sweep over the pole pieces of the electromagnet, a spring biasing said armature to rotate it in clockwise direction and to thereby operate the clock mechanism, said armature being arranged to rotate through an angle of predetermined magnitude alternately in a clockwise and counter-clockwise direction, the position of the armature at the end of its movement in a clockwise direction corresponding to a run down condition of the spring and the position of the armature at the end of its counter-clockwise movement corresponding to a fully re-stressed condition of the spring, a switch including a fixed contact and a movable contact, and means to close said switch at the end of the clockwise movement of the armature, to maintain said switch in closed position during the counter-clockwise movement of the armature and until the spring is fully re-stressed, said means including an arm pivoted on said armature to rotate about an axis parallel and in spaced relation to the rotational axis of said armature and offset from the longitudinal axis of said armature said arm carrying said movable contact; said fixed contact being adjacent one pole of the magnet which pole is cooperatively arranged in relation to one end of the armature and the axis of rotation of said arm being intermediate the rotational axis of the armature and the other end thereof, the armature, movable arm and switch members being thereby arranged to effect closing of said switch at the end of the clockwise movement of the armature and to effect movement of the movable contact in sliding engagement with the fixed contact during counter-clockwise movement of said armature; and cooperating magnetic elements on said pivoted arm and electromagnet respectively, to maintain said switch in closed condition by maintaining said sliding engagement during counter-clockwise movement of said armature.

movement of said armature, and a magnetic member extending from one pole piece of the electromagnet and adapted to concentrate the magnetic flux and a cooperating magnetic member carried by the pivoted arm, to maintain said switch in closed condition by maintaining said sliding engagement during counter-clockwise movement of said armature.

5. In apparatus of the character described, in combination an electromagnet having a longitudinal axis and a pair of poles, an elongated armature pivoted to rotate about an axis passing through the mid-point of the electromagnet and perpendicular to the axis thereof, said armature having a longitudinal axis perpendicular to its rotational axis, said longitudinal axis lying in a plane parallel to the plane containing the longitudinal axis of the electromagnet and said armature having end pieces arranged to sweep over the pole pieces of the electromagnet, a spring biasing said armature to rotate it in clockwise direction and to thereby operate the clock mechanism, said armature being arranged to rotate through an angle of predetermined magnitude alternately in a clockwise and counter-clockwise direction, the position of the armature at the end of its movement in a clockwise direction corresponding to a run down condition of the spring and the position of the armature at the end of its counter-clockwise movement corresponding to a fully re-stressed condition of the spring, a switch including a fixed contact and a movable contact, and means to close said switch at the end of the clockwise movement of the armature, to maintain said switch in closed position during the counter-clockwise movement of the armature and until the spring is fully re-stressed and then to open said switch said means including an arm pivoted on said armature to rotate about an axis parallel and in spaced relation to the rotational axis of said armature and offset from the longitudinal axis of said armature said arm carrying said movable contact; said fixed contact being adjacent one pole of the magnet which pole is cooperatively arranged in relation to one end of the armature and the axis of rotation of said arm being intermediate the rotational axis of the armature and the other end thereof, the armature, movable arm and switch members being thereby arranged to effect closing of said switch at the end of the clockwise movement of the armature and to effect movement of the movable contact in sliding engagement with the fixed contact during counter-clockwise movement of said armature; and cooperating magnetic elements on said pivoted arm and electromagnet respectively, to maintain said switch in closed condition by maintaining said sliding engagement during counter-clockwise movement of said armature and a spring biasing said pivoted arm to open said switch at the end of said counter-clockwise movement.

6. In apparatus of the character described, in combination an electromagnet having a longitudinal axis and a pair of poles, an elongated armature pivoted to rotate about an axis passing through the mid-point of the electromagnet and perpendicular to the axis thereof, said armature having a longitudinal axis perpendicular to its rotational axis, said longitudinal axis lying in a plane parallel to the plane containing the longitudinal axis of the electromagnet and said armature having end pieces arranged to sweep over the pole pieces of the electromagnet, a spring biasing said armature to rotate it in clockwise

11

direction and to thereby operate the clock mechanism, said armature being arranged to rotate through an angle of predetermined magnitude alternately in a clockwise and counter-clockwise direction, the position of the armature at the end of its movement in a clockwise direction corresponding to a run down condition of the spring and the position of the armature at the end of its counter-clockwise movement corresponding to a fully restressed condition of the spring, a switch including a fixed contact and a movable contact, and means to close said switch at the end of the clockwise movement of the armature, to maintain said switch in closed position during the counter-clockwise movement of the armature and until the spring is fully restressed and then to open said switch said means including an arm pivoted on said armature to rotate about an axis parallel and in spaced relation to the rotational axis of said armature and offset from the longitudinal axis of said armature said arm carrying said movable contact; said fixed contact being adjacent one pole of the magnet which pole is cooperatively arranged in relation to one end of the armature and the axis of rotation of said arm being intermediate the rotational axis of the armature and the other end thereof, the armature, movable arm and switch members being thereby arranged to effect closing of said switch at the end of the clockwise movement of the armature and to effect movement of the movable contact in sliding engagement with the fixed contact during counter-clockwise movement of said armature, and a magnetic member extending from one pole piece of the electromagnet and adapted to concentrate the magnetic flux and a cooperating magnetic member carried by the pivoted arm, to maintain said switch in closed condition by maintaining said sliding engagement during counter-clockwise movement of said armature and a spring biasing said pivoted arm to open said switch at the end of said counter-clockwise movement.

7. In apparatus of the character described, in combination an electromagnet having a longitudinal axis and a pair of poles, an elongated armature pivoted to rotate about an axis passing through the midpoint of the electromagnet and perpendicular to the axis thereof, said armature having a longitudinal axis perpendicular to its rotational axis, said longitudinal axis lying in a plane parallel to the plane containing the longitudinal axis of the electromagnet and said armature having end pieces arranged to sweep over the pole pieces of the electromagnet, a spring biasing said armature to rotate it in clockwise direction and to thereby operate the clock mechanism, said armature being arranged to rotate through an angle of predetermined magnitude alternately in a clockwise and counter-clockwise direction, the position of the armature at the end of its movement in a clockwise direction corresponding to a run down condition of the spring and the position of the armature at the end of its counter-clockwise movement corresponding to a fully restressed condition of the spring, a switch including a pair of electric contact pins made of pure silver, one of said pins being fixed and the other movable, the axes of said pins being transverse to each other, and means to close said switch at the end of the clockwise movement of the armature, to maintain said switch in closed position during the counter-clockwise movement of the armature and until the spring is fully restressed and then to open said switch, said means including a pivot on said armature and

12

an arm pivoted on said pivot to rotate about an axis parallel and in spaced relation to the axis of rotation of said armature said arm carrying said movable contact pin, said armature and pivoted arm thereon being arranged to cause the end of the movable pin on said arm to extend beyond and in contact with the fixed pin when the armature is at the end of its clockwise movement and to draw said movable pin across and in contact with the fixed pin during counter-clockwise motion of the armature, the said pivot moving away from said fixed contact during said counter-clockwise motion.

8. In apparatus of the character described, in combination an electromagnet having a longitudinal axis and a pair of poles, an elongated armature pivoted to rotate about an axis passing through the mid-point of the electromagnet and perpendicular to the axis thereof, said armature having a longitudinal axis perpendicular to its rotational axis, said longitudinal axis lying in a plane parallel to the plane containing the longitudinal axis of the electromagnet and said armature having end pieces arranged to sweep over the pole pieces of the electromagnet, a spring biasing said armature to rotate it in clockwise direction and to thereby operate the clock mechanism, said armature being arranged to rotate through an angle of predetermined magnitude alternately in a clockwise and counter-clockwise direction, the position of the armature at the end of its movement in a clockwise direction corresponding to a run down condition of the spring and the position of the armature at the end of its counter-clockwise movement corresponding to a fully restressed condition of the spring, a switch including a fixed contact and a movable contact, and means to close said switch at the end of the clockwise movement of the armature, to maintain said switch in closed position during the counter-clockwise movement of the armature and until the spring is fully restressed, said means including an arm pivoted on said armature to rotate about an axis parallel and in spaced relation to the rotational axis of said armature and offset from the longitudinal axis of said armature said arm carrying said movable contact; said fixed contact being adjacent one pole of the magnet which pole is cooperatively arranged in relation to one end of the armature and the axis of rotation of said arm being intermediate the rotational axis of the armature and the other end thereof, the armature, movable arm and switch members being thereby arranged to effect closing of said switch at the end of the clockwise movement of the armature and to effect movement of the movable contact in sliding engagement with the fixed contact during counter-clockwise movement of said armature, and a magnetic member extending from one pole piece of the electromagnet and adapted to concentrate the magnetic flux and a cooperating magnetic member carried by the pivoted arm, to maintain said switch in closed condition by maintaining said sliding engagement during counter-clockwise movement of said armature, said fixed contact comprising a pair of metallic bars insulated from each other, and the movable contact comprising an elongated U-shaped metallic member adapted to bridge said fixed contacts at the end of said clockwise movement and to remain in sliding engagement therewith during said counter-clockwise movement.
